UNITED STATES PATENT OFFICE.

GEORGE L. DAMON, OF PITTSBURG, PENNSYLVANIA.

MOUNTING HEAVY DOORS OF SAFES AND VAULTS.

No. 908,448.

Specification of Letters Patent.

Patented Jan. 5, 1908.

Application filed September 16, 1907. Serial No. 393,180.

To all whom it may concern:

Be it known that I, GEORGE L. DAMON, a citizen of the United States, residing at Pittsburg, in the county of Allegheny and State of Pennsylvania, have invented certain new and useful Improvements in Mounting Heavy Doors of Safes and Vaults, of which the following is a specification.

This invention relates to mountings for heavy doors of safes, vaults or the like.

The users of large safes and vaults have heretofore had a great deal of trouble with the heavy doors. This trouble has been due to the fact that, when the hinges of a door of this type wear slightly, the center of the door sags to such an extent that the door in some instances has been closed with difficulty and in other instances cannot be closed without the assistance of experienced help with lifting appliances. To overcome this difficulty a pressure system has been employed to force the door to its seat but this system while effective when the door does not sag too far, is of no use when the lower edge of the door drops below the door seat.

In an application previously filed by me, I disclose a construction in which the door is sustained in such a manner that the door may be readily brought into the seating position by raising or preferably depressing the door either from a position into which it has settled from some yielding in its mounting or from a slightly raised position, any suitable pressure system being employed, if desired, in connection with the mounting.

The present invention has for an object to accomplish this same result by a new and useful means in which the door is movably supported on its mounting and counter load- ed in such a way as to facilitate raising it to its seat by the application of a comparatively very small force, or depressing it to its seating position without inconvenience.

In carrying out my invention I employ a lever system by which the weight of the door is sustained either in whole or in part upon its mountings and a counter-loading means, which nearly, quite, or over-balances the door by acting through the lever system in opposition to the weight of the door.

My invention will be fully understood upon reference to the accompanying drawings, in which—

Figure 1 is a front elevation of a vault

door with its mounting, in which one form 55 of my invention is embodied; Fig. 2 is a section on line 2—2, Fig. 1; Fig. 3 is a view similar to Fig. 1, having applied thereto a modified embodiment of my invention in which the counterload in the form of a weight 60 is yielding held in normal position by means of springs; Fig. 4 is a view similar to Fig. 1, in which an adjustable spring constitutes the counterload which operates through the medium of the lever system. 65

Referring to all of the figures, 1 represents the vestibule, of a fire and burglar-proof vault and 2 the heavy door fitted to the doorway in the vestibule preferably by the well known type of ground joint. 70

3 represents a Crane hinge, 4 the pintle of said hinge having bearings 5 and 6, and 7 the swivel connection between the door and the hinge; these parts together comprising an illustrative type of door mounting, by which 75 the door is mounted in opening and closing relation to the doorway. In order to permit the door to move vertically relatively to its mounting, the swivels 7 are vertically movable in the Crane hinge 3 and are sus- 80 tained vertically by the short arms 8 of levers 9 which are fulcrumed at 10 and connected at their outer ends with suitable counterloading means springs and weights for example to be described. 85

The counterloading means is such that acting through the long arms of levers 9, it has an elevating power equal to or varying slightly from the load imposed by the door acting through the short arms of the levers, 90 so that the door can be readily centered, notwithstanding it may be slightly out of center with the doorway in consequence of some inaccuracy or settling or wear in the mounting; that is to say, whether the counter- 95 loading effect is slightly less than the load imposed by the door, or equal to said load or slightly in excess thereof, it will require application of very little additional force to bring the door to the proper seating position. This may be applied either by causing the door to slide over any suitable guiding surface, such for instance as the lower or upper inclined surfaces of the jamb, thereby assisting or opposing the counterload's influence 100 upon the door, according to circumstances. 105

According to the embodiment shown in Fig. 1, the counterload consists of a weight

11 acting against the long arms of the levers and of sufficient dimensions to overbalance the door so that the weight may rest lightly upon the step 12 when the door is open but 5 may be raised from said step to permit the door to find its seat or under the increased load that might be transmitted to the door through the handle 13 in the act of closing the door. The weight may be conveniently 10 mounted upon a hollow sleeve 14 and through said sleeve connected with the levers by means of wrist bearings 15 at the ends of said sleeves.

According to the form shown in Fig. 3, the 15 counterloading means is a weight 11² held in intermediate position on the pintle 4 by means of springs 16 which are given a definite set. If the door should become off center, the necessary force may be applied to it 20 in either direction to compress one of the springs and permit the door to center.

According to the form shown in Fig. 4, the counterload consists of a spring 17 adapted to exert pressure against the upper wrist 25 bearing which serves as a shoulder, and transmits it through the sleeve 14 to the lower lever. By means of a nut 18, the pressure of a spring 17 may be adjusted so that it will overbalance the weight of the door, thus 30 necessitating a slight depression of the door to seat it, or the tension of the spring may be such that it will only sustain the door at or below its center but with sufficient tendency to expand to perform the main work in raising the door to its seating position.

Inasmuch as claims covering the broad idea of this invention, have been included in my co-pending application, Serial No. 393,181, certain broad claims which could 40 have been made upon the subject-matter of the present application, have not been embodied therein.

Having thus described my invention the following is what I claim as new therein and 45 desire to secure by Letters Patent:

1. In combination with a door, a lever system which sustains the entire weight of the door; and a counterload acting upon said lever system in opposition to the weight of the 50 door.

2. In combination with a mounting for heavy doors, upon which the door has relative vertical movement, a lever system through which the entire weight of the door 55 may be sustained on its mounting, and a counterload acting through the lever system in opposition to the weight of the door.

3. In combination with the mounting for heavy doors, a lever system mounted on said 60 mounting, by which the entire weight of the door may be sustained vertically, and a

counterweight acting on said lever-system in opposition to the weight of the door.

4. In combination with a safe or vault having a doorway and a door; the mounting for 65 the door by which it is carried to and from the doorway; a lever-system fulcrumed on the mounting and sustaining on one side of the fulcrum, the weight of the door; and a counterload acting upon the lever-system on 70 the opposite side of the fulcrum and in opposition to the weight of the door.

5. In combination with a heavy door; a lever-system suitably arranged to travel with said door during its opening and closing 75 movements, and adapted to sustain the entire weight of the door during such movements; a pintle about which said door swings in opening and closing; and a counterweight arranged concentrically with said pintle and 80 acting on the lever-system in opposition to the weight of the door.

6. In combination with a heavy vault or safe door, a counterloaded door-sustaining lever-system sustaining the entire weight of 85 said door and tending to raise it upward, and traveling with the door in its opening and closing movements.

7. In a mounting for heavy doors, the combination of a supporting lever-system adapted to sustain the entire weight of the door; and a counterweight and spring opposing the descent of said door through said lever-system.

8. In a mounting for heavy doors, the combination of a supporting lever-system adapted to sustain the entire weight of the door; a counterweight and spring opposing the descent of the door through said lever-system; and a spring limiting the action of said weight 100 and the spring first named.

9. In a mounting for heavy doors, the combination therewith, a counterloaded lever-system moving bodily with the door in its opening and closing movements, said lever-system being adapted to sustain the entire weight of the door and tending to lift the door.

10. In a mounting for heavy doors, the combination of a counterloaded lever-system 110 bodily moving with the door in its opening and closing movements, sustaining the entire weight of the door and tending to lift the same; and a yielding means opposing the raising movement of the lever-system.

The foregoing specification signed at Pittsburgh Pa., this 3rd day of April, 1907.

GEORGE L. DAMON.
